APPARATUS FOR COMPRESSING AIR

Charles H. Taylor, Toronto, Ontario, Canada

Application August 26, 1937, Serial No. 161,155

2 Claims. (Cl. 230—105)

The invention relates to improvements in a method and apparatus for compressing air as described in the present specification and shown in the accompanying drawings that form a part of the same.

One object of the invention is to provide a simple and efficient method for compressing air wherein by providing a continuous circulation of the water through two relatively superimposed segregated bodies of stored water and trapping the entrained air, the necessity of creating a water head, or fall, is eliminated.

Another object of the invention is to eliminate the great expense and inconvenience incidental to supplying a continuous stream of water, by pipe line, or otherwise, for compressing air at points far removed from a natural source of water, as is necessary with any of the types of hydraulic air compressors heretofore known.

A further object is to provide apparatus for compressing air which will operate with little, or no, loss of power, or efficiency and will therefore produce an exceptionally large body of air under extremely high pressure.

And generally the objects of the invention are to provide simple air compressing apparatus which can be produced and installed at very little cost, will function indefinitely with practically no attention and which will give a higher degree of efficiency than has heretofore been possible.

The invention consists in the novel features of construction, arrangements and combinations of parts described in the present specification and more particularly pointed out in the claims for novelty following.

In describing my invention reference will be made to the accompanying drawings, in which:

Figure 1 is a vertical sectional view through the liquid storage receptacle showing the circulating and compressing apparatus, portions of the various elements being shown in vertical section.

Figure 2 is an enlarged central vertical sectional view through the intake end of the compression tube, taken on the line 2—2 of Figure 3.

Figure 3 is a plan view of the structure shown in Figure 2.

Figure 4 is an enlarged side elevation of the circulating pump, a portion of the wall being broken away.

Like numerals of reference indicate corresponding parts in the various figures.

In the preferred embodiment of my invention I employ a liquid storage receptacle having the required surface area and depth to meet the re-

quirements of the installation being made, and intermediate of the depth of such storage receptacle, I provide a horizontal partition 1 whereby to divide the said receptacle into two distinct and separate liquid chambers, 2 and 3 respectively one positioned above the other, and communicating with each other, in a manner to be described in detail hereinafter, whereby the liquid, with which the chambers are filled, may be circulated from one chamber to the other.

A tubular member 4 suitable for the conveyance of liquid and entrained air is projected through an opening in the partition 1 and extends downwardly from a point below the surface of the superimposed unconfined body of liquid in the upper chamber, completely through said body of liquid and into the confined body of liquid, terminating somewhat short of the bottom of the lower chamber 3. The lower end of the tube 4 is preferably flared, as shown at 3a to increase the volume of the flow in discharge from the tube.

A hollow head 5 is secured to the top end of the tube 4 and forms an upward continuation thereof terminating below the surface of the unconfined body of liquid. The opening within the head is of considerably greater diameter than the bore of the tube 4, as shown at 5a and is reduced downwardly, as at 6, to the point of communication with the bore of the tube whereby to permit of the entry of a large body of liquid, and entrained air and to decrease the volume of the flow into the tube 4.

A plurality of tubes 7 extended through the top of the head 5 and terminating below the surface of the unconfined body of liquid provide means for admitting the liquid to the tube.

8 is a trap positioned within the confined body of water and surrounding the lower portion of the tube 4, whereby the circulated liquid and entrained air is emitted from said tube within the confines of said trap. The trap is open at the bottom and is supported in spaced relation to the bottom of the storage receptacle so as to permit of the water from the tube 4 passing through the trap into the surrounding body of water.

The top of the tank, or trap, 8 is preferably, although not necessarily, substantially conical in shape and extends upwardly around the tube 4 in spaced relation thereto a considerable distance before joining therewith, whereby to provide a storage chamber 9 into which the air entrained with the liquid in passage through the tube 4 is adapted to rise under the pressure of the two bodies of liquid as the liquid heretofore confined

by the tube is discharged into the confined body of liquid.

- 10 is a substantial conical deflecting member positioned beneath the lower end of the tube 4 with its apex preferably extending into the mouth of said tube and tending to break up the flow of liquid from the tube and cause the entrained air to separate from the liquid and rise into the chamber 9.
- 10 11 is an air pipe leading from the interior of the chamber 9 and provided with a suitable valve 12 whereby to control the discharge of air from said chamber.
- 13 is a pipe leading from a point within the body of water in the trap 8, through the air chamber 9 and through the surrounding liquid into the outside atmosphere for the purpose of providing a blow off to prevent the air in the chamber going below the lower end of the tube 4.
- 20 14 is a tube extending upwardly from within the confined body of liquid, through the horizontal partition 1, at a point considerably removed from the tube 4, and terminating at substantially the surface of the unconfined body 25 of liquid.
- A pump 15 is mounted in that portion of the tube 14 which extends into the lower, or confined, body of liquid and in operation provides an upward flow of liquid from the confined body of 30 water to the surface of the upper, or unconfined, body of liquid and thence to the inlet tubes 7 in the head of the tube 4 for re-delivery to the lower chamber by means of said tube 4. A shaft 16 having operating connection with a motor 17, 35 or other suitable driving power, extends downwardly through the tube 14 and serves to operate the pump 15.

While it is not my intention to limit the present application to any specific form of pump it being understood that any type of pump suitable to the purpose may be used, I have found the pump shown herein, comprising a plurality of short propellers 18 mounted on the shaft 16 and spaced by separators 19, to be extremely advantageous in that it provides a steady, straight flow 45 of water.

The tube 14 is preferably gradually enlarged from the discharge end of the pump upwardly whereby to increase the volume of the flow from the pump. Said tube 14 is also provided with flared intake 20.

In the operation of this invention the storage receptacle is filled with water or other liquid until the surface of the liquid in the upper chamber 55 is slightly above the inlet tubes 7 in the top of the vertical tube 4. The pump is then set in motion causing liquid to be drawn from the lower chamber and deposited at the surface of the unconfined upper body of liquid. Through the action of the pump the liquid at the surface of the unconfined body of liquid is caused to flow 60

towards the inlet tubes 7 and downwardly therethrough into the tube 4 drawing with it air from the outside atmosphere. The liquid and entrained air is confined within the tube 4 throughout the depth of the upper body of liquid and partly through the confined body of liquid and deposited through the flared discharge end of the tube on to the conical deflector 10 within the trap 8, by means of which deflector the flow is broken up causing the air to separate and to rise 10 through the surrounding liquid into the top portion 9 of the trap under pressure of the liquid and to be stored there for delivery through the outlet pipe 11. The liquid emitted from the tube 4 flows beneath the trap into the surrounding body of liquid as the upward flow of liquid caused by the action of the pump progresses. This cycle of operations continues throughout the operation of the pump, with the liquid being circulated thereby through the segregated bodies 20 of liquid and in each downward flow through the tube 4 drawing air with it into the trap 8 in which the air is separated and trapped while subjected to pressure by both bodies of liquid.

While I have shown and described my invention as embodied in the form which I at present consider best adapted to carry out its purposes, it will be understood that it is capable of modifications, and that I do not desire to be limited in the interpretation of the following claims except 30 as may be necessitated by the state of the prior art.

What I claim as my invention is:—

1. A means for producing air under pressure comprising a confined body of liquid, a superimposed unconfined body of liquid, a tubular member extending from practically the surface of the unconfined body of liquid and terminating within the confined body of liquid, means for trapping and storing the air delivered by said tubular member within the confined body of liquid, a tubular impeller casing positioned partly within the confined body of liquid and partly within the unconfined body of liquid, and an impeller operating within said casing.

2. Air compressing apparatus comprising a storage receptacle having a horizontal partition dividing said receptacle into upper and lower liquid chambers, a tubular liquid discharge member extending through said partition and terminating at its opposite ends within the liquid in said upper and lower chambers respectively, means for trapping and storing air delivered by said tubular member within the lower body of liquid, a tubular impeller casing extending through said horizontal partition and terminating at its ends within the liquid in the upper and lower chambers respectively, and an impeller mounted in said casing to force liquid from the lower to the upper chamber.

CHARLES H. TAYLOR.
